AUTOMATIC DIAPHRAGM PRESS

Richard W. Stanley, Lockport, N. Y., assignor
to Merritt Engineering & Sales Co., Inc., Lock-
port, N. Y., a corporation of New York

Application December 31, 1936, Serial No. 118,505

8 Claims. (Cl. 144—281)

This invention relates to presses and more particularly to the diaphragm type of veneer presses adapted for producing plywood and similar pressed materials.

An object of the invention is to provide an improved construction and control for the operation of diaphragm presses such as described in the co-pending application Serial Number 744,132 of Ericsson H. Merritt, filed September 15, 1934, now issued as Patent No. 2,148,704, dated February 28, 1939.

The principal object of the present invention is to provide a diaphragm press having full automatic operation in combination with the features of minimum mass in the head driving mechanism and minimum size in the head driving motor.

Other objects of the invention will in part be obvious and will in part appear hereinafter.

The invention accordingly comprises the features of construction, combination of elements, arrangement of parts exemplified in the construction hereinafter set forth; their scope of application being clearly indicated in the appended claims.

To the accomplishment of the foregoing and related ends, the invention, then, comprises the features hereinafter fully described, and particularly pointed out in the claims, the following description setting forth in detail certain illustrative embodiments of the invention, these being indicative however of but a few of the various ways in which the principle of the invention may be applied.

For a fuller understanding of the nature and objects of the invention reference should be had to the following detailed description taken in connection with the accompanying drawings, in which:

Figure 1 is a side view of a single opening press embodying the invention, imposed upon which is a wiring diagram showing the electrical circuit involved in one particular application of the invention.

Figure 2 is a section of a solenoid operated valve showing it in a discharging position.

Figure 3 is a detailed sectional plan showing the diaphragm clamps.

Figure 4 is a detailed view showing the diaphragm means and the associated members on an enlarged scale.

The diaphragm type presses first constructed for hot plate veneering, plywood formation and similar operations did not provide for the admission of fluid to partly inflate the diaphragm

prior to final closing of the press. Owing to the top head having to be moved down onto the work mechanically to "close up the daylight" as it is termed in the art the material being pressed was thereby tightly clamped between the head 5 and the base prior to the application of the diaphragm pressure. This movement, being effected by the power operated rotation of large nuts which actuated the downward travel of the head along the strain rods, ended by a jambing of the 10 nuts upon their threads when the head came to rest on the work. The diaphragm actuated pressing operation then took place, but upon its completion, forces of an impractical magnitude were required to overcome the frictional resistance of 15 the nuts so they could be rotated in reverse to open the press to the desired extent. When a press of this character was supplied with steam heated plates and used as a hot-press, it was also found difficult to provide heat-insulating 20 means which would withstand the high mechanical pressures involved without destruction or loss of efficiency. Since the press operating diaphragm was of rubber or similar organic material it was desirable to protect it from excessive 25 temperature. Thus the first diaphragm presses presented two imperfectly solved problems in the excessive resistance to easy opening resulting from the jambing action at the end of the closing movement and the excessive tendency of the 30 rubber diaphragm to become heated.

With the foregoing and other considerations in mind the present invention solves these troublesome problems by providing means whereby the press closes against a cushion of fluid pressure in 35 a partly inflated diaphragm which upon completion of the pressing operation is completely deflated, thus freeing the material being clamped under reactive pressure between the head and base, thereby permitting the head to be raised 40 quickly and easily from the closed position.

Furthermore one of the means for accomplishing this result involves a spring supported platen above and urged away from the diaphragm chamber so that whenever the press is in an open 45 position, metallic contact is broken between the heated members of the press and the diaphragm chamber thus cutting off the flow of heat from the steam platen to the diaphragm by interposing an air space between them.

The press illustrated in Figure 1 comprises base 50 10 which carries for instance four strain rods 12. Placed above the base 10 is a head 11 which is vertically adjustable with respect to the posts. Resiliently mounted on base 10 is platen 14 sup- 55

ported by four springs 30. To the top surface of the platen is attached steam plate 15 and to the lower side of head 11 is attached steam plate 18. Steam plates 15 and 18 are provided with steam chambers and are of metal so that their surfaces may rapidly be brought to a high temperature so as to hot press plywood assemblies, as indicated at 17, or other materials to be hot pressed.

In accordance with the invention the head member is adjustably supported by means wherein it can be readily lowered until the steam plates 18 rest upon the work, and there is interposed between the platen member 14 and the base 10 means whereby a high pressure may be developed so as to exert the necessary pressing of the work for bonding or other purposes.

As exemplified, the means for adjustably supporting the head member 11 comprises supports 20 carrying internally threaded rotatable nuts 21 which fit over externally threaded portions 22 on each of the strain rods 12. In order to rotate the nuts 21 there is provided suitable means which may include a two way electric motor 23 carried by bracket 24.

The shaft 25 of the motor is provided with sheaves 26 connected by a suitably disposed belt 27 to sheaves 28 on rotatable sleeves 29 which are integral with the nuts 21 and each of which is mounted in bushing 29a of support 20. Accordingly when the motor is operated the head 11 and the parts carried thereby are readily lowered against the work 17. As the plate 18 comes against the work, the motor may be turned off by any suitable means, one type of which is hereinafter exemplified.

Since the rotation of the nuts 21 by the motor does not exert sufficient pressure for the usual bonding operation or other operations to be performed by the press, there is provided, between the platen 14 and the base 10, diaphragm means whereby a chamber for the reception of fluid pressure is provided. In the present instance there is illustrated diaphragm means consisting of a sheet of rubber 40 clamped throughout its entire periphery to the top of base 10 and is secured to the base by frame 43 and bolts 44. The space between the diaphragm sheet 40 and the top surface of the base 10 forms the diaphragm chamber, for the reception of fluid pressure, and as particularly clearly seen in Fig. 1, the frame 43 also surrounds and forms a guide for the diaphragm plate 46. Fluid, for example, water, introduced under pressure through the tubular members 41 readily works its way under the diaphragm, forcing the diaphragm sheet away from the top surface of the base 10 and exerting an upward pressure upon the diaphragm plate 46 sufficient to perform the required pressing action between the platens. The inlet 41a is unique in being beveled or recessed. This results in remarkable advantages of averting valve-action by the diaphragm against the edges, and of providing evenness of feed. The diaphragm plate 46 fits closely with the frame 43 and in conjunction with frame 43 forms a metallic restraining casing when the flexible diaphragm sheet 40 is inflated, just as the casing or shoe of a pneumatic tire restrains the innertube from over expansion. A pressure, for example, of 200 pounds per square inch may be applied in the case of the pressing of an ordinary plywood assembly. The upward movement of the flexible diaphragm sheet 40 may be as much as an inch and a quarter.

The press is shown in Figure 1 at the position 75 just prior to final closing.

In order to minimize the migration of heat from the steam plate 15 through the platen 14 to the diaphragm 46, and also to provide a movable member to effect an automatic operating cycle after the head 11 has descended so as to take up all of the daylight between the platens 15 and 18 and the work 17, platen 14 is suspended on springs 30, a distance *c* above the diaphragm plate 46 when the press is in the opened position. To effect an automatic operating cycle and to provide for the release of the work 17 after the fluid pressure has been exhausted from the diaphragm chamber an arrangement as shown in Figure 1 may be utilized. This includes control circuits and a magnetic switch 52, the latter being of any well-known commercial form in which a three wire line supply L', L², L³, is connected through respective sets of contacts O and C by electro-magnetically operated switch bars 5, 6, the bar 5 and its associated structure serving to bridge the contacts in the set C for energizing the motor 23 to close the press, and the switch bar 6 with its associated structure serving to bridge the set of contacts O for reversely energizing the motor to open the press. The magnetic relay switch 52 is provided with control circuits c¹, c², c³, c⁴, c⁵, which are in circuit with respective controlling means, including a manually-operated switch 50 to be employed by the operator for closing the press, and a manually-operated switch 61 to be employed by the operator for opening the press. In control-connection also is a switch 54 which is mechanically operated near the end of the closing movement of the press, being carried for this purpose on the platen 14 to come in contact with an adjustable stem 55. The switch 54 is normally closed, and on striking the actuating stem 55 is opened, thus breaking the circuit controlling the motor 23 and stopping the press against over-run. The stem 55 being adjustable, permits of the close regulation of the down cut-off point. Another similar switch 64 on the head 11, is normally in closed position, but in its path there is arranged an actuating stop 65, which when contacted, opens the switch 64 to shut off the current to the motor 23 and again stop the latter against over-run. Another switch 56, carried by the platen 14, is arranged in a control circuit with a magnetic switch 58 to control the same, the latter being in a circuit with a solenoid 59 whose plunger is arranged to operate a valve 60 between the fluid-pressure pump and the expandible diaphragm 40. The platen-carried switch 56 is arranged to be operated by a stem 61, preferably resilient, and mounted on the base 10. The circuit through the solenoid 59 thus subject to the control of the magnetic switch 58 is connected in parallel with the magnetic switch 52, to the line-supply L', L³. In circuit in connection also with the main operating switches 50, 61, is a further control switch 63 which is operated by a small pressure-diaphragm on the conduit system 47 between the pump and the press. The press is shown at the position just prior to final closing. The "close" push button 58 has been manually depressed, thus closing the down circuit to the head motor 23 through the down side of the reversing switch 52, thus causing the head to descend and contact the work 17. Further descent of the head causes depression of the platen 14, distance *a* so that in the position shown the platen 14 is distance *b* above the diaphragm plate 46. At this instant the normally closed limit switch 54 mounted on platen 14 has contacted adjustable stem 55 thus causing the 71

limit switch to open the down circuit to the head motor 23. At the same instant the normally open solenoid valve limit switch 56 also mounted on platen 14 has contacted the resilient stem 57 mounted on the base, thus closing the circuit to solenoid valve switch 58 and energizing solenoid 59, thereby opening valve 60 to permit passage of water from the pump to the diaphragm through pipes 41.

10 After the down circuit to the head motor has been broken by the opening of the limit switch 54 the head 11 and the parts attached thereto may coast downward due to the inertia of their mass and thus decrease distance c, but during 15 this time water is being admitted to the diaphragm chamber and raising the diaphragm plate 46 also decreasing the distance c so that when the head comes to rest there must of necessity be some degree of inflation of the dia- 20 phragm so that the diaphragm plate 46 is raised to some extent above its normal position when the press is open.

In actual operation if a sufficient degree of inflation of the diaphragm cannot be secured before the head 11 comes to rest, the contact rod 25 55 may be so adjusted as to break the down circuit of the head motor by the initial downward movement of the platens 14. Also the normal distance c between the bottom surface of 10 the platen 14 and the diaphragm 46 may be increased by adjusting the springs 30 on their studs 31 by means of the nut 32.

In instances where it is desirable to operate the head up and down at extremely high speeds, the 15 head motor 23 may be equipped with a solenoid brake so that the coasting of the head 11 due to its inertia can be held within very close limits, thus insuring the essential partial inflation of the diaphragm prior to complete closing of the 10 press.

When the pressing operation is complete, the "open" push button 61 is manually depressed thus first breaking the circuit to the solenoid valve switch 58 and de-energizing the solenoid 59 so that under the influence of spring 62 the 5 solenoid valves assume a position as shown in Figure 2, permitting the fluid in the diaphragm chamber to return to the supply tank. Second, the depression of the "open" button 61 closes the 0 "up" circuit to the head motor 23 as far as the switch 63, and this "up" circuit is completely closed when the pressure in the diaphragm chamber falls to a pre-determined level, permitting the closing of the pressure limit switch 63, which, 5 being in communication with the diaphragm chamber of the press has its plunger 63a, Fig. 2, pushed up by the same pressure fluid, and correspondingly by its stem 63b and switch stem 63c holds the switch bar 63d off of the switch contact 63e; but when the pressure falls as predetermined the switch bar bridges the contacts 63e and completes the circuit to close contactor 53 of reversing switch 52 and energizing the head motor 23 causes it to raise the head 11 on the strain rods 12. Under the influence of the head motor the head continues to rise until the limit switch 64 contacts the adjustable stop 65, opening the "up" circuit.

Other modes of applying the principle of the invention may be employed, change being made as regards the details described, provided the features stated in any of the following claims, or the equivalent of such, be employed.

I hereby particularly point out and distinctly 5 claim as my invention:

1. A press, comprising relatively movable members, mechanical means to move at least one of said members, a platen movably mounted on one of said members, fluid-expansible diaphragm means between said platen and its associated member, means for releasing fluid from said diaphragm means, and means actuated by the drop in pressure in the diaphragm means for starting the operation of the said mechanical means to open the press, whereby binding resistance against the opening movement is eliminated. 5

2. A press, comprising relatively movable members, an electric motor to move at least one of said members, a platen movably mounted on one of said members, an expansible rubber diaphragm sheet between said platen and its associated member, a diaphragm plate and means in common for securing the diaphragm sheet and guiding the diaphragm plate, said means including a frame surrounding said diaphragm plate as a guide 20 therefor and for clamping the edges of said diaphragm sheet to its associated press member, a fluid-pressure connection having a beveled inlet between said sheet and its associated member, a valve for controlling flow of pressure fluid to 25 and from the space between said expansible rubber sheet and its associated member, a manually actuated electric switch for opening said valve to release pressure fluid, an electric switch actuated by predetermined drop in pressure in said 30 diaphragm means for starting the motor to open the press, switch means for automatically stopping the motor when the press is open, switch means for starting the motor to close the press, and cooperating electric switch means for admitting the pressure fluid to the diaphragm before 35 the press is closed, and switch means for automatically stopping the motor when the press is closed. 35

3. A press, comprising relatively movable members, an electric motor to move at least one of said members, a platen movably mounted on one of said members, an expansible rubber diaphragm sheet between said platen and its associated member, a diaphragm plate and means in common for securing the diaphragm sheet and guiding the diaphragm plate, said means including a frame surrounding said diaphragm plate as a guide 40 therefor and for clamping the edges of said diaphragm sheet to its associated press member, a fluid-pressure connection having a beveled inlet between said sheet and its associated member, a valve for controlling flow of pressure fluid to and from the space between said expansible rubber sheet and its associated member, a manually actuated electric switch for opening said valve to release pressure fluid, an electric switch actuated by predetermined drop in pressure in said 45 diaphragm means for starting the motor to open the press, switch means for automatically stopping the motor when the press is open, switch means for starting the motor to close the press, and cooperating electric switch means for admitting the pressure fluid to the diaphragm before the press is closed. 50

4. A press, comprising relatively movable members, an electric motor to move at least one of said members, a platen movably mounted on one of said members, an expansible rubber diaphragm sheet between said platen and its associated member, a diaphragm plate and means in common for securing the diaphragm sheet and guiding the diaphragm plate, said means including a frame surrounding said diaphragm plate as a guide therefor and for clamping the 55 60 65 70 75

- edges of said diaphragm sheet to its associated press member, a fluid-pressure connection having a beveled inlet between said sheet and its associated member, a valve for controlling flow of pressure fluid to and from the space between said expansible rubber sheet and its associated member, a manually actuated electric switch for opening said valve to release pressure fluid, an electric switch actuated by predetermined drop in pressure in said diaphragm means for starting the motor to open the press, switch means for starting the motor to close the press, and co-operating electric switch means for admitting the pressure fluid to the diaphragm before the press is closed.
5. A press, comprising relatively movable members, an electric motor to move at least one of said members, a platen movably mounted on one of said members, an expansible rubber sheet between said platen and its associated member, a frame surrounding said platen as a guide therefor and for clamping the edges of said rubber sheet to its associated press member, a fluid-pressure connection having a beveled inlet between said sheet and its associated member, a valve for controlling flow of pressure fluid to and from the space between said expansible rubber sheet and its associated member, a manually actuated electric switch for opening said valve to release pressure fluid, an electric switch actuated by predetermined drop in pressure in said diaphragm means for starting the motor to open the press, and switch means for automatically stopping the motor when the press is closed.
10. A press, comprising relatively movable members, an electric motor to move at least one of said members, a platen movably mounted on one of said members, an expansible rubber sheet between said platen and its associated member, a frame surrounding said platen as a guide there-
15. 6. A press, comprising relatively movable members, an electric motor to move at least one of said members, a platen movably mounted on one of said members, an expansible rubber sheet between said platen and its associated member, a

for and for clamping the edges of said rubber sheet to its associated press member, a fluid-pressure connection having a beveled inlet between said sheet and its associated member, a valve for controlling flow of pressure fluid to and from said expansible rubber sheet, a manually actuated electric switch for opening said valve to release pressure fluid from the diaphragm means, and an electric switch actuated by predetermined low pressure under said rubber sheet for starting the motor to open the press.

7. A press, comprising relatively movable members, mechanical means for moving at least one of said members, a platen movably mounted on one of said members, fluid-expansible diaphragm means between said platen and its associated member, a valve for controlling flow of pressure fluid to and from said diaphragm means, a manually actuated electric switch for opening said valve to release pressure fluid from the diaphragm means, an electric switch actuated by predetermined low pressure in said diaphragm means for starting the mechanical means to open the press, means for starting the mechanical means for closing the press, and cooperating electric switch means for admitting pressure fluid to the diaphragm means before the press is closed.

8. A press, comprising relatively movable members, mechanical means for moving at least one of said members, a platen movably mounted on one of said members, fluid-expansible diaphragm means between said platen and its associated member, a valve for controlling flow of pressure fluid to and from said diaphragm means, a manually actuated electric switch for opening said valve to release pressure fluid from the diaphragm means, and a switch actuated by predetermined low pressure in said diaphragm means for starting the mechanical means to open the press.

RICHARD W. STANLEY. 40
